Inventor:

George G. Allard,
by: *H. Bradbury*
Attorney.

UNITED STATES PATENT OFFICE.

GEORGE G. ALLARD, OF ST. PAUL, MINNESOTA.

SURGICAL INSTRUMENT.

1,308,728.

Specification of Letters Patent.

Patented July 1, 1919.

Application filed October 29, 1918. Serial No. 260,084.

To all whom it may concern:

Be it known that I, GEORGE G. ALLARD, a citizen of the United States, residing at St. Paul, county of Ramsey, and State of Minnesota, have invented a new and useful Improvement in Surgical Instruments, of which the following is a specification.

The object of this invention is to provide an improved form of surgical instrument which is particularly adapted for removing adenoids, tonsils and other growths from the passage connecting the nose and throat and to provide an instrument of this kind with means for cutting and holding the tissue around the growth so that the cutting members will when operated make a clean and efficient cut for removing a growth. With these and other objects in view my invention comprises the features of construction and combination of parts hereinafter more particularly described and claimed. In the accompanying drawing forming part of this specification Figure 1 is a side elevation of my invention; Fig. 2 is a plan view; Fig. 3 is an end view; Fig. 4 is a section taken on the line X—X of Fig. 1, and Fig. 5 is a section taken on the line Y—Y of Fig. 1.

In the drawing, A indicates an operating stem upon which the parts of my instrument are suitably mounted, said support being in the form of a long shank having a handle member 2 on one end and formed with a holder or guard B on its opposite end. This holder or guard has two upwardly and outwardly curved sides 3 and 4 connected at their upper ends by the cross bar 5 the said parts being disposed angularly to the stem A and extending above the same. The guard is adapted to be held firmly against the wall of the passage between the nose and throat with the growth to be removed protruding through the opening in the guard. The bar 5 is formed with a cut edge 6 which will cut into and release a portion of the tissue when the guard is pressed into position for use. Disposed over the inner faces of the sides 3 and 4 and of the bar 5 are a pair of shearing blades 7 and 8 which are formed with a pair of forwardly extending shafts 9 and 10. These shafts are journaled in supports 11 and 12 which are detachably fastened upon the shank A by screws 13 or other suitable means. The movement of the shearing blades 7 and 8 when the shafts 9 and 10 are turned is back

and forth across the opening in the guard B. The shearing blades 7 and 8 have inwardly directed cutting edges 14. Thus when the shafts 9 and 10 are turned and the shearing blades closed the growth projecting through the opening in the holder B and partly released by the cutting of the tissue by the blade 6 is sheared completely away and removed. The ends of the shafts 9 and 10 adjacent to the handle 2 are formed with a pair of crank arms 15 and 16 the outer ends of which are provided with a pair of swiveled threaded blocks 17 and 18, through which a right and left handled threaded screw shank 19 is free to turn. One end of said screw shank has a knurled head 20 which is adapted to be turned by hand to revolve the screw shank and said screw shank is provided with a guide pulley 21 having an annular groove 22 in which a stationary guide 23 mounted upon the shank A is fitted. The guide pulley holds the threaded shank 19 causing a movement lengthwise thereof and thus causing the screw shank to swing the arms 15 and 16 and close or open the cutting blades 7 and 8 when the head 20 is turned. The guide pulley 21 moves up and down on the guide 23 when the shank 19 is turned to compensate the movement of the blocks 17 and 18 and arms 15 and 16. The instrument can easily be adjusted and held with the holder B placed against the wall of the passage between the nose and throat and with the growth to be cut away protruding through the holder. While so held the shearing blades can easily and quickly be efficiently closed to remove the growth.

In accordance with the patent statutes I have described the principles of operation of my invention together with the apparatus which I now consider to represent the best embodiment thereof, but I desire to have it understood that the construction shown is only illustrative and that the invention can be carried out by other means and applied to uses other than those above set forth within the scope of the following claims.

Having described my invention, what I claim as new and desire to protect by Letters Patent is:—

1. A surgical instrument comprising, in combination, an operating stem having a laterally disposed loop forming a tissue holder, a pair of shearing blades coöperating with said holder and movably mounted upon said

stem for transverse movement across the holder, and means operable from the outer end of said stem for closing and opening said blades.

5. 2. A surgical instrument comprising, in combination, an operating-stem having a laterally disposed loop forming a tissue holder, a portion of said loop being formed with a tissue cutting blade, a pair of shear-

10 ing blades coöperating with said loop to

effect a shearing action across the open space in said loop, a pair of shafts journaled and disposed longitudinally upon said stem, and upon which said pair of blades are mounted, and screw operating means connected 15 with said shafts for turning them to effect the shearing action of said pair of blades.

In witness whereof I have signed my name to this specification.

GEORGE G. ALLARD.
